UNITED STATES PATENT OFFICE.

PHILIP BERNARD, OF SIOUX CITY, IOWA.

CHICKEN-WATERER.

1,211,054.

Specification of Letters Patent. Patented Jan. 2, 1917.

Application filed April 29, 1916. Serial No. 94,436.

To all whom it may concern:

Be it known that I, PHILIP BERNARD, a citizen of the United States, residing at Sioux City, in the county of Woodbury and State of Iowa, have invented a new and useful Chicken-Waterer, of which the following is a specification.

The present invention relates to an improved chicken waterer of the portable type. An object of this invention is to provide a device of this character, which will automatically feed the water to the chickens, will keep the water in a sealed receptacle from dust and dirt, will heat the water when desired, and which, when taken apart, comprises but three cylinders or drums, each fully open at one end to permit access thereto for cleansing, filling, and adjusting.

Another object of this invention is to provide a chicken waterer of this character with a drinking trough, which extends entirely about the receptacle, so as to feed the water to a large number of chickens at the same time; and to provide a construction wherein the water receptacle and its base or heater may be separated, and wherein each is provided with a bail to permit the carrying of the same independently of the other.

A further object of the invention is to provide a receptacle which may be easily and quickly filled without the use of a funnel, or other filling device, and simply by dumping or pouring the water directly into the upper free end of the receptacle when open.

Other objects and advantages of the invention will be brought out in the following specific disclosure of the present preferred embodiment, the same being illustrated in the accompanying drawings, wherein:

Figure 1 is a perspective view of a complete chicken waterer constructed according to this invention. Fig. 2 is an enlarged vertical central section of the same. Fig. 3 is a detail enlarged section, taken through the base of the waterer at right angles to the showing in Fig. 2. Fig. 4 is a detail perspective view of the water receptacle and its trough removed from the base, the view being on a reduced scale. Fig. 5 is a detail perspective view of the base showing the bail thereof raised for carrying the base independently of the receptacle, the scale of this figure being the same as Fig. 4.

Referring to these drawings, wherein like parts are designated by similar numerals of

reference throughout the several views, 10 designates the base or lower section of the device. This base is in the form of a cylinder having a bottom 11 closing its lower end 60 and provided a short distance above the bottom with an inwardly pressed bead 12 adapted to support a second or false bottom 13, which is soldered in place. Between the bottoms 11 and 13 there is provided an oil 65 receptacle into which projects a wick 14 which extends downwardly from a suitable lamp 15 carried upon the intermediate portion of the false bottom 13. The false bottom 13 is provided with an upwardly extending nipple 16 closed by a cap or the like, and by means of which the oil is adapted to be introduced for filling the oil space.

The base section, as shown to advantage in Fig. 3, is open, free and unobstructed at its 75 upper end. The base section is preferably formed from sheet metal, and the upper edge thereof is shown as being rolled outwardly about a reinforcing wire in the usual manner. The base section 10 is also provided 80 near its upper and lower ends with openings 17 in the sides thereof to permit the free circulation of air upwardly through the same. In order to easily carry the base section 10, a bail 18 is provided. The bail is placed 85 within the section and has its hooked ends 19 passed outwardly through the opposite sides of the same and overturned in the usual manner, so as to hingedly support the bail. The bail 18 is also relatively long, so 90 that when the bail is swung down into the base section, it strikes the false bottom 13 and rests thereon at one side of the lamp or burner 15. The hooked ends 19 are offset in this manner for the purpose of permitting 95 the ready raising and lowering of the relatively long bail 15.

The upper section or receptacle of this invention is adapted to fit down into the upper open end of the base section 10, and 100 to rest upon the upper edge of the latter. This receptacle comprises a pan 20, the peripheral wall of which fits snugly into the upper open end of the base section 10, and is provided with an outstanding annular 105 flange 21 at its upper edge, which flange is of sufficient width to extend outwardly over the upper edge of the base section 10, and has its outer edge rolled downwardly to provide a lip 22 for engagement upon the 110 beaded upper end of the base section. It will be noted that the flange 21 is pressed

inwardly at its inner edge to form a rounded upper edge on the wall of the pan.

The pan 20 has secured thereto, and as a part thereof, an upstanding outer cylinder 23, which comprises part of the water receptacle. This cylinder 23 is of less diameter than the pan 20, is flanged at its lower end, and is secured concentrically upon the bottom of the pan, leaving a space between it and the wall of the pan. The outer cylinder 23 has an outlet opening 24 at one side below the upper edge of the wall of the pan 20, which outlet opening 24 is closed by a removable plug 25. One or more of these openings 24 may be provided, although but one is shown in the present instance. The outer cylinder 23, as shown in Fig. 2, is of uniform diameter throughout, and has an upper open free end. The upper edge of the sheet metal, from which the cylinder 23 is formed, is preferably rolled over outwardly to provide a bead on said upper edge. The upper receptacle also comprises an inner cylinder 26, which is of slightly less diameter than that of the cylinder 23 and is adapted to telescope down into the latter. The lower end of the cylinder 26 is open and uninterrupted, being provided with no bead, or the like. The upper end of the inner cylinder 26 is provided with a permanent top 27 in the form of a disk of sheet metal, which has its marginal edge turned downwardly and inwardly about an outstanding annular flange formed upon the upper end of the inner cylinder 26. This outstanding flange is relatively wide so that it stands out from the cylinder 26, and provides a sealing and supporting flange 28 which projects annularly over the upper edge of the outer cylinder 23. Thus, the inner cylinder is supported from dropping down too far within the outer cylinder 23, and the space between the cylinders is sealed by the overlapping supporting flange or shoulder.

The permanent top 27 is provided with a strap handle 29 secured across the central portion thereof, and which is adapted to be grasped for the purpose of lifting the inner cylinder 26 out of the outer cylinder 23. An air vent 30 is formed in the top 27 and is normally closed by a plug 31. By removing the plug 31, the inner cylinder 26 may be easily raised and lowered for opening and closing the receptacle.

The pan 20 is designed to fit tightly within the base 10, so that when the receptacle is lifted, the base 10 may be lifted therewith. However, by overcoming the frictional engagement between the pan 20 of the upper section and the base section 10, the upper receptacle may be lifted from the base section and may be carried and used independently thereof, when it is not desired to heat the water within the receptacle.

This is shown in Fig. 4. To permit the easy carrying of the upper receptacle, the outer cylinder 23 is provided near its upper end, and at diametrically opposed points, with a pair of ears 32 riveted or otherwise secured against the outer face of the cylinder 23. A bail 33 has its opposite ends looped through the apertures in the ears 32 to hingedly connect the bail 33 to the ears. The bail 33 is of sufficient length to admit of its being swung down into the position shown in Fig. 1 against the side of the receptacle. It will be noted from Fig. 2 that the bail 18 of the base section 10 has its hooked ends 19 secured through the sides of the base at a point spaced below the pan 20, so as not to interfere with the positioning and removal of the upper receptacle.

To fill the upper receptacle, the plug 25 is forced into the opening 24 to close it. The plug 31 is removed from the inner cylinder to admit air through the vent 30. The rigid handle 29 is grasped and drawn upwardly to lift the inner cylinder 26 out of the cylinder 23. Water is now poured, pumped, or in any other manner introduced into the upper end of the cylinder 23 to fill the same to the desired height. With the plug 31 still removed, the inner cylinder 26 is telescoped into the cylinder 23 and forced downwardly therein until the supporting shoulder 28 of the inner cylinder seats upon the upper edge of the outer cylinder. The plug 31 is now screwed into place. The plug 25 may now be removed to permit water to flow through the opening 23 into the trough formed between the wall of the pan 20 and the outer cylinder 23. The water rises in the pan until the atmospheric pressure against the surface of the exposed water is sufficient to retain the column of water in the receptacle. In the usual manner, the water is automatically fed to the trough from time to time as it is used, the water remaining substantially at the same height in the trough.

When it is desired to carry the receptacle a distance to fill the same with water, it is not necessary to carry the base section 10 thereof, as the upper receptacle may be lifted upwardly from the base and carried independently of the same by means of the bail 33. When it is not desired to carry the entire device from one place to another, the two sections may be separated by lifting the upper receptacle with its pan 20 out of the top of the base 10. The bail 18 may be swung upwardly out of the base 10 and grasped for carrying the base in one hand, while the bail 33 may be grasped in the other hand to carry the upper receptacle. In this manner the weight of the device may be distributed at opposite sides of the person carrying the waterer, and the device may thus be divided into sections which are

easily handled. When it is not desired to heat the water, the base section 10, may, of course, be stored away, as the receptacle is provided with the trough as a part thereof, 5 and has a flat bottom to support the receptacle upon the ground.

From Fig. 2, it will be noted that the inner cylinder 26 terminates in a plane above the opening 24, so that the inner 10 cylinder 26 may be turned into any desired position within the outer cylinder 23. This arrangement admits of the quick and easy removal and replacement of the inner cylinder 26, for no care need be exercised, and 15 no time need be lost in securing an exact and predetermined adjustment of the cylinders 23 and 26 before the same may be telescoped one into the other.

What is claimed is:—

- 20 1. A chicken waterer comprising a cylindrical base section having a closed bottom and an open upper end, a false bottom spaced from and located above the bottom of the section and providing an oil space 25 between the two bottoms, a lamp supported upon the false bottom and a bail hinged to the walls of the base section within the latter and adapted to be swung upwardly out of the open upper end of the base section 30 for carrying the same, or swung downwardly so as to rest upon the false bottom in spaced relation to and away from the lamp.
  - 25 2. A chicken waterer comprising a cylindrical base section open at its upper end, a heating element in the base section, an upper section detachably fitting upon the upper end of the base section and adapted
- to contain water, a bail mounted on the upper section for carrying the latter and for 40 carrying the two sections when in assembled relation, and a second bail hinged to the base section and being adapted to be swung down wholly within the base section and at one side of the heating element to 45 permit the assembling of the sections, and being adapted to be swung upwardly out of the base section for carrying the same when the sections are separated.
3. In a chicken waterer, a pan, a cylinder 50 carried in the pan and being of less diameter than the same to provide an annular trough about the cylinder, said cylinder having an open top and having a relatively small lateral opening below the upper edge 55 of the pan, a second cylinder telescoping into the top of the first cylinder and having an annular supporting and sealing flange at its upper end and having a permanent top closing the upper end of the second cylinder, a handle on the permanent top for withdrawing the second cylinder to permit the filling of the first cylinder and for replacing the second cylinder, and a regulatable air vent in said permanent top to 60 permit the passage of air into and from the second cylinder upon the positioning and removal of the same.

In testimony, that I claim the foregoing as my own, I have hereto affixed my signature in the presence of two witnesses.

PHILIP BERNARD.
